UPHOLSTERY TRIM PANEL

Meredith S. Randall, Detroit, Mich., assignor to
 Woodall Industries Incorporated, Detroit,
 Mich., a corporation of Michigan

Application October 25, 1935, Serial No. 46,731

8 Claims. (Cl. 154—45.9)

My invention relates to improvements in upholstery trim panels and particularly to those intended for use in the interior of an automobile body.

5 An object is to provide a trim panel which presents the same appearance as an expensive upholstery trim panel and which may be easily fabricated and at a low cost. My improved panel is durable and of a sturdy construction. It is 10 self-supporting.

It comprises a foundation lamination, a lamination of wadding, a relatively thin flexible embossed lamination overlying the wadding, and preferably a layer of suitable upholstery material 15 such as upholstery cloth overlying the embossed lamination.

Heretofore in the fabrication of trim panels provided with wadding or padding to give a rich upholstered appearance, it has been the practice 20 to sew the upholstery trim fabric to the foundation board through the wadding along determined lines to outline the desired upholstery design. It has also been the practice to provide sections of wadding of predetermined shape and 25 size and to fabricate these sections into the panel to give it the desired appearance.

Stitching through the foundation lamination produced a line of weakness along the line of stitching which was highly undesirable. Fabrication of a panel in this fashion was also an expensive operation. I propose to so fabricate a panel that it will present the same appearance as a panel wherein the wadding has been stitched to the foundation board. My fabricated panel 35 will employ wadding so as to give the soft cushion effect and appearance but the stitching is eliminated, and the panel furthermore possesses advantages and features of superiority due to its novel fabrication.

40 A meritorious feature of my invention resides in the provision of a lamination of relatively thin flexible material possessing thermoplastic characteristics and being self-sustaining which is adapted to be embossed to present a determined 45 design and to permanently retain said embossed contour, which layer overlies a layer of wadding being spaced by the wadding from the foundation lamination. This embossed layer preferably holds the wadding against the foundation 50 layer and holds it to the shape of the embossed design. Upholstery trim cloth is preferably spread over the embossed layer and adhesively secured thereto. The complete panel presents upon its upholstered surface the design of the 55 embossment given to the thermoplastic layer.

The wadding underneath gives the padded effect. The foundation layer may be built of thermoplastic material such as asphalt impregnated fiber board (K B board is a commercial variety which is acceptable) or it may be of plain fiber board as it is not necessary that the foundation layer be capable of embossment.

The several advantages, meritorious features, and objects of my invention will more fully appear from the following description, appended 10 claims, and accompanying drawing, wherein:

Figure 1 is a side elevation of a trim panel embodying my invention.

Fig. 2 is a cross-sectional view through a fragment of a panel, 15

Fig. 3 is a cross-sectional view through another fragment of the panel, and

Fig. 4 is a cross-sectional view through the complete panel showing the several laminations which make up the same, 20

While it has heretofore been commercially practiced to form a panel by adhesively securing upholstery cloth direct to a thermoplastic fibrous foundation board and then embossing this structure so as to simulate an upholstered panel, such 25 constructions lacked the soft cushioning character and appearance of a true upholstered panel wherein wadding or padding was employed. Upholstered panels employing wadding are very old and in fabricating the same there is generally used a foundation board over which the wadding is spread and upholstery cloth overlies the wadding. To give the desired upholstered effect a common practice is to stitch the upholstery 30 cloth through the wadding to the foundation 35 board. In many cases the wadding is cut to a definite design so that there are raised areas, where the wadding is employed, and debossed areas in the finished product between the areas of wadding. This method of fabrication is expensive and it requires hand labor and stitching of the material.

By my improved invention I fabricate a trim panel which employs wadding, but I do not stitch the wadding or upholstery cloth to provide 45 an embossed design. I obtain the embossed effect through other means. While I have shown it in a trim panel such as is employed in the interior of automobile closed bodies it might be employed in various plans.

In the embodiment illustrated the foundation lamination is indicated as 10. It may be formed of fiber board or other suitable material. If desired this foundation layer may be of a moisture 50 resistant fibrous material such as a composition 55

fiber board carrying a moisture resistant binder such as asphalt. A form sold commercially under the name of K B board has been found acceptable.

Upon one surface of this foundation layer I 5 juxtapose a layer of felt or other suitable wadding 12 in the form shown. This wadding, as shown, does not extend to cover the entire area of the foundation layer but it might so extend if it were so desired. This material may be a good grade 10 of hair felt or paper felt or any other suitable soft deformable cushioning material such as is capable of being used for this purpose.

I then provide a layer of thermoplastic material which may be a layer of thin strong fibrous 15 asphalt impregnated material such as the K B board above mentioned which is capable of being embossed under heat and pressure and of permanently retaining its embossed shape. This layer of material is normally self-form sustaining 20 in that it will retain the curvature and embossed design given to it. It is, however, relatively thin and flexible. In the drawing it is indicated as 14. To this layer of thermoplastic material 4 I secure a layer or covering of upholstery material 16. Any type of upholstery material such as 25 suitable fabric, or the like may be used. These two layers 14 and 16 are adhesively secured together. They are stamped to the desired embossed design. The layer 14 will permanently 30 retain this design and hold the covering layer 16 thereto. This two ply structure is then juxtaposed over the wadding 12 as shown in Fig. 4. It is adhesively secured to the foundation layer 10 along the margin beyond the wadding. This 35 upholstery covering is folded over unto the back as shown at 18. The indentations and debossments 20 in the layer 14 force their way into the easily compressible felt so that the wadding is held by the embossed layer against the foundation 40 layer to the design embossed in layer 14 and while the embossed design is determined by the layer 14 this layer is supported throughout the extent of the wadding by the soft wadding material so that a true upholstered appearance 45 and character results with the wadding yielding underneath the upholstery layer to pressure brought to bear against the upholstery so as to present the appearance of an expensive upholstered panel.

50 In the particular construction shown there is an embossed bead 24 outside the margin of the wadding. It is apparent that if desired the marginal portion of the layer 14 might be otherwise decoratively embossed or that the combined 55 thickness of the margin of layers 10 and 14 might be decoratively embossed.

This particular construction is inexpensive and simple to manufacture. It does not require any careful hand operations or any stitching or the 60 like.

What I claim:

1. A laminated trim panel comprising, in combination, a foundation lamination, a lamination of wadding juxtaposing the foundation lamination, and a relatively thin flexible layer of embossed and self form sustaining composition fi-

brous material overlying the wadding and secured to the foundation lamination.

2. A laminated trim panel comprising, in combination, a foundation lamination, a lamination of wadding juxtaposing the foundation lamination, and a relatively thin flexible layer of self sustaining embossed thermoplastic composition fibrous material secured to the foundation lamination overlying the wadding and holding it to the foundation lamination. 5

3. A laminated trim panel comprising a foundation layer of fibrous material, a layer of wadding overlying one surface of the foundation layer, a relatively flexible layer of fibrous material impregnated with a thermoplastic binder and carrying an embossed design and being self-form sustaining overlying the wadding and holding the wadding to said design against said foundation layer. 10

4. A laminated trim panel comprising a foundation layer of fibrous material impregnated with a thermoplastic binder, a layer of wadding overlying one surface of the foundation layer, a layer of embossed fibrous material impregnated with a thermoplastic binder and being of a self-form sustaining character overlying the wadding and upholstery cloth overlying said last named layer. 15

5. A laminated trim panel comprising a self-supporting moisture resistant foundation layer, 20 a layer of wadding overlying one surface thereof, an embossed self-form sustaining layer of fibrous material impregnated with a thermoplastic binder and overlying the wadding and secured to the foundation layer holding the wadding 25 thereagainst, said embossed layer holding the wadding to the embossed design of said embossed layer and upholstery trim material overlying said embossed layer. 30

6. An upholstery trim panel comprising a foundation layer, a layer of wadding overlying a portion of one surface of the foundation layer, a layer of thermoplastic embossed self-form sustaining material overlying the wadding and provided with an embossment encircling the wadding 45 beyond the margin thereof, said last named layer being secured to the foundation layer beyond the margin of the wadding. 40

7. A laminated panel comprising a foundation layer, a layer of wadding overlying a portion of one surface of the foundation layer, an embossed self sustaining layer of fibrous material containing a thermoplastic binder adhesively secured to the foundation layer beyond the margin of the wadding and positioning the wadding upon the 50 foundation layer and upholstery covering material extending over said wadding and layer of fibrous material and adhesively secured in place. 55

8. A laminated structure comprising two layers of fibrous material each impregnated with a thermoplastic binder, at least one of said layers having a design embossed therein and being of a self-form sustaining character, and a layer of wadding interposed between said layers of fibrous thermoplastic material. 60
